United States Patent Office.

ELI J. MANVILLE, OF WATERBURY, CONNECTICUT, ASSIGNOR TO BLAKE & JOHNSON, OF SAME PLACE.

Letters Patent No. 79,368, dated June 30, 1868.

IMPROVEMENT IN DEVICE FOR STOP-MOTION FOR REVOLVING SHAFTS.

The Schedule referred to in these Letters Patent and making part of the same.

TO ALL WHOM IT MAY CONCERN:

Be it known that I, ELI J. MANVILLE, of Waterbury, in the county of New Haven, and State of Connecticut, have invented, made, and applied to use a certain new and useful Improvement in Stop-Motions for Revolving Shafts; and I do hereby declare the following to be a full, clear, and exact description of the said invention, reference being had to the annexed drawing, making part of this specification, wherein—

Figure 1 is an elevation of the clutch endwise of the shaft.

Figure 2 is a section vertically through the shaft and clutch at the line z z , fig. 1.

Figure 3 is an elevation of the parts with the driving-pulley removed, and

Figure 4 is the pulley detached, showing the side that comes next the coupling-key.

Similar marks of reference denote the same parts.

In stop-motions for power-presses, looms, and many classes of machines, the clutch that connects the driving-pulley and shaft is disconnected at the proper time, but the momentum of the parts is such that they continue to move, often at the risk of injury to the machine or the attendant, and frequently the parts stop at the wrong point.

The present invention is to insure the stopping of the parts that are moved at a definite point, simultaneously with the disconnecting of the motor; and said invention consists in a latch-stop, fitted to be slidden laterally and parallel with the shaft that is being revolved, in combination with a clutch-key passing crosswise of the shaft, and connecting the same with the pulley or other motor, so that when the latch-stop is moved, its end operates upon said key, to disconnect the same from the pulley; and this latch also becomes a stop, to prevent the shaft turning any further by the momentum, after the power is disconnected.

In the drawing, a is the shaft to be revolved, b is the pulley or wheel to which the motive-power is applied.

Upon the shaft a is a hub, c , in which is a key, d , sliding crosswise of the shaft, and having a shank, e , around which is a spring, f , that tends to keep the head of the key towards the shaft a , but at the same time allow the key to be moved by the latch g , acting between the projecting head, 2, of said key d and the hub c , as hereafter described.

The hub c has a recess in its end, within which is the circular hub 3 of the pulley b , and in this hub 3 is a notch, 4, (see fig. 4.)

When the key d is in the normal position, shown in figs. 1 and 2, the shaft a and pulley b are connected, and revolve together, but when the key d is drawn out by the action of the latch-stop, taking under the head 2, the shaft a is disconnected from the pulley or motor b .

The red lines at d , fig. 1, show the position of the head of the key when drawn out by the latch g .

The latch g also becomes the stop against which the key-head 2 comes into contact, and hence the shaft a , and parts connected thereto, cannot be turned beyond the proper point by the momentum.

The latch-stop is fitted to be slidden laterally, and parallel, or nearly so, with the axis of the shaft a , so as to be in a position to pass under the head, 2, of the key d , and stop the shaft a , or be drawn laterally from under that head, 2, and allow the spring f to draw the key into the notch 4, and connect the shaft a and motor b . The mechanism for giving this lateral movement to the latch-stop g might be varied. I have, however, represented a simple and efficient device, as follows:

The latch-stop g is mounted upon a hollow axis, h , passing into the frame or support l , and m is a spring, tending to move the latch and its axis laterally towards the key d .

Through the hollow axis h is a bolt, h' , upon the projecting end of which is a cam-lever, n , confined by the screw-nut or head of the bolt. The cam n acts, when the lever n is drawn down, to pull the latch-stop g away from under the head 2, and when the lever is relieved by the action of a treadle, or any other connection, the spring m projects the latch-stop into position to withdraw the key d .

What I claim, and desire to secure by Letters Patent, is—

1. The key *d*, sliding across the shaft to be moved, to couple or uncouple the same, with the motor, substantially as set forth, in combination with a latch-stop, moved laterally, substantially as specified, to operate upon said key and stop the revolution of the shaft, as set forth.
2. The latch-stop *g*, mounted upon a hollow axis, in combination with the cam-lever *n* and key *d*, substantially as and for the purposes set forth.

In witness whereof, I have hereunto set my signature, this 18th day of May, 1868.

ELI J. MANVILLE.
